UNITED STATES PATENT OFFICE.

JOSEPH A. PETERMAN, OF BROOKLYN, NEW YORK.

SASH-OPERATING MECHANISM.

1,418,732.

Specification of Letters Patent. Patented June 6, 1922.

Application filed August 12, 1920. Serial No. 403,065.

To all whom it may concern:

Be it known that I, JOSEPH A. PETERMAN, a citizen of the United States, and a resident of Brooklyn, in the county of Kings and 5 State of New York, have invented certain new and useful Improvements in a Sash-Operating Mechanism, of which the following is a specification.

This invention relates to sash operating 10 mechanism and particularly to that class adapted to be employed in connection with ventilators, skylights or other structures wherein movably mounted sashes are employed and designed to be quickly opened or 15 closed as the occasion demands.

The invention is an improvement upon the form of device or mechanism shown and described in my Patent No. 1,320,568 of November 4, 1919, and an object of the 20 invention is to provide a positive means which will satisfactorily meet the requirements of statutes and municipal ordinances for automatically controlling the ventilator or skylight of a building or theatre at the time of 25 fire and establish a vent or outlet for smoke and flames and produce a draft which will cause the smoke and flames to be conducted from the auditorium.

Another object of the invention is to 30 provide a ventilator or skylight embodying a plurality of weight actuated sashes and a thermally actuated means therefor which will operate to positively cause at least one or more of the sashes to open automatically 35 at the time of the fire.

Figure 1, is a plan view of the mechanism constructed in accordance with my invention, parts being broken away.

Figure 2 is a vertical section therethrough. 40 Figure 3 is a side view of a slightly modified form of the invention.

Figure 4 is a side view of a slightly modified form of the invention.

In carrying the invention into practice, 45 use is made of a frame 5 of any suitable well known construction, closed at its top by glass panels 6 and open at its bottom. The said frame is mounted upon the customary curbing 7 which preferably rises for a distance of about three feet from the roof 8 so that the sashes of the frame which I will refer to hereinafter will not be obstructed by snow. The frame is formed with vertical sides 9—9 and corresponding ends 10—10 50 and as illustrated sash openings 11 are provided in said side and ends respectively in

which swinging sashes 12 are mounted. In the present instance, these sashes are pivoted at 12' to the adjacent lower walls of the sash openings. These sashes are substantially of the same construction as those shown and described in my prior patent aforesaid and while I have stated that they are pivoted at their lower edges, this should be treated as simply illustrative of a preferred manner of mounting the same. I would not care to confine myself to this showing inasmuch as any well known form of swinging sash can be employed if desired. 70

Below the open bottom of the frame 5 and extending clear across the same is a wire protecting screen 13 which serves to prevent the panels 6, when broken, from falling past said screen. It is stated that in order 75 to obtain a maximum vent or opening in the skylight at the time of fire, it is customary to break the glass top of the skylight to permit of direct passage of the smoke and flames through the structure. Sometimes 80 the heat from the escaping flames breaks the glass at the top of the skylight and were it not for the screen 13, the falling glass might cause injury to persons beneath the skylight. 85

Each of said swinging sashes 12 is provided with an opening mechanism 14, the same comprising a bracket 15 to which the outer end of a link 16 is pivoted, the inner end of said link having pivotal connection 90 with a link 17, a swinging weight 18 having connection with the mechanism at the juncture of said links 16 and 17. The link 17 extends downward and outward from the inner end of the companion link 16 and its 95 lower or outer end is pivoted to the adjacent sash 12. The pivot pins 18, 19 and 20 embodied in the mechanism 14 are formed of non-corrosive material so that no undue binding will be created between the moving parts of said mechanism incident to the action of moisture.

The weight 18 normally depends from the pivot pin 19 and the tendency thereof to normally pull in a downward direction 105 against the inner end of the link 16 and push against the upper end of the companion link 17. The pivot 18 is connected with the sash and disposed with such regard to the hinge mounting of the latter 110 whereby as the links 16 and 17 operate to straighten out as shown in dotted lines in

Figure 1, the full force of the weight 18 exerts its influence against the sash to open same.

The means for normally holding the several sashes closed embodies a cross bar 21 located in the frame 5 intermediate between the upper and lower ends of the sash openings 11 and rising therefrom and secured at its upper end to the rib 22 of the frame 5 is a fixed vertical standard 23 on which a runner 24 is free to slide. From each one of the swinging sashes 12 is extended a cord or controlling connection 25, attached at its inner end to said runner. In each of said cords is a fusible link 26 of any well known construction so that on its destruction, the sash with which it is associated, will open instantly under the force of the weight 18 and action of the links 16 and 17. The leverage action of the link 17 against its sash is such that a relatively small weight will satisfactorily spend its force to open a relatively heavy sash. The links 16 and 17 are also arranged to mutually serve as a stop to limit the opening movement of the sash. The runner has connection with a manually actuated rope 27 which passes over a suitable guide pulley 28 and extended to the stage or "prompter's desk" where it can be quickly had when wanted. This arrangement permits the sashes to be opened for ordinary ventilating purposes when desired. While I have stated that the connections 25 are of cord, it follows that this is only necessary to assure the fullest measure of safety of operation of the structure. Metal cables could be used but cords are preferred in view of their flexibility and the fact that should the fusible link 26 by any chance fail to operate at the requisite moment, the cord will be destroyed by the action of the flame itself.

In Figure 3, 28' represents a manually actuated connection similar to 27 in the first form of my invention. A thermally responsive device 29 is arranged in said connection and the same consists of a lever 30 with which the branch 31 of the connection is secured. A second lever 32 is pivoted to the lower end of the lever 30 so that a crotch 33 is produced between both levers for the reception of the cross pin 34 of a bail 35, the latter carried by the branch 31' of said connection 28. The lever 32 extends upward from the base of the lever 30 and at an angle thereto so that the crotch 33 is of substantially V-form. The levers 30 and 32, are provided with rows of perforations 34 and 35' respectively and fusible links of the type shown at 36 may be connected with a set of two of such perforations in respective levers. The construction offers a means whereby the levers 30 and 32 are capable of sustaining relatively different loads, it being understood that the power of the levers

increases in a direction away from the pivotal point between said levers and as the link fuses, the lever 32 turns on its pivot to instantly eject the bail 35. In this form, it is not necessary that each of the sash cords 70 25 be provided with a fusible link.

In Figure 4, the link 17^a of the sash opening mechanism 14^a is formed of sections 17^b and 17^c, a sliding rod 17^d having connection between said sections. The ends of the rod 75 pass into openings 17^e in said sections 17^b and 17^c and the same are headed at 17^f. Heavy cushioning springs 17^g are interposed between the heads 17^f and the cross bars 17^h of the link sections so that said sections will 80 separate against the action of the springs and absorb the shocks and jars on the opening of the sash.

While I have described that weights 18 are preferred so that the sashes will open 85 quickly, I find that when the links are formed of material, the weight of which is properly calculated with regard to the weight and resistance offered by the sashes, the latter open freely and said weights may 90 be entirely eliminated. This is due to the manner of connecting the links 16 and 17 together and their connection with the said sashes 12 and frame 5.

What I claim as my invention is:

1. A structure having an opening, a sash movable over said opening, a pair of weighted sash moving links between the sash and the structure, a fusible device for holding the sash closed against the action of said 100 links and means included in the links for cushioning the movement of the sash, said links pivoted together and one of said links having pivotal connection with the structure above the said opening, and the other of said 105 links having pivotal connection with the said sash.

2. A thermally actuated sash operating mechanism including a frame having an opening and a sash movable over said opening, a travelling runner, a flexible connection between the runner and the sash for moving the latter, means for manually actuating the runner, a fusible link in said connection, and means for exerting an opening 115 influence against the sash on destruction of the fusible link or on manual operation of said connection through said runner, said opening means comprising a normally horizontally disposed link pivoted to the frame 120 above the opening and a normally inclined link pivoted at one end to said first named link and at its opposite end to the sash.

3. A structure including a frame having an opening therein, a sash pivoted in said opening, means for holding the sash in a closed position, and a plurality of links pivoted together and respectively pivoted to the sash and to said frame, and normally disposed with relation to the pivot of the sash 130

so that when the holding means is released, the combined weight of said links will act against said sash to open the same.

4. In a sash operating mechanism, a frame having vertical portions with openings therein, swinging sashes mounted on the frame and associated with the aforesaid openings to normally close same, an opening means for each of said sashes, said means comprising a link pivoted at its outer end to the frame and a second link inclined with relation to the first named link and having its upper end pivoted thereto and its lower end pivoted to the sash, the links serving in their act of straightening relatively, to apply their force against the sash and give a starting movement thereto in a direction to uncover the mating opening, and means for moving the sashes simultaneously to closed positions, said moving means serving to normally hold the sashes closed against the action of their aforesaid opening means.

5. In a sash operating mechanism, a frame having vertical portions with open-

ings therein, swinging sashes mounted on the frame and associated with the aforesaid openings to normally close same, an opening means for each sash, said means comprising a link pivoted at its outer end to the frame and a second link inclined with relation to the first named link and having its upper end pivoted thereto and its lower end pivoted to the sash, the links serving in their act of straightening relatively, to apply their force against the sash and give a starting movement thereto in a direction to uncover the mating opening, and means for moving the sashes simultaneously to closed positions, said moving means serving to normally hold the sashes closed against the action of their aforesaid opening means, the links further serving when straightened relatively to limit the opening movement of their respective sash.

Signed at Brooklyn, in the county of Kings, and State of New York, this 9th day of July, A. D. 1920.

JOSEPH A. PETERMAN.
